UNITED STATES PATENT OFFICE.

WALTER FERRIS, OF MILWAUKEE, AND MATTHEW F. KEESE, OF SOUTH MILWAUKEE, WISCONSIN, ASSIGNORS TO BUCYRUS COMPANY, OF MILWAUKEE, WISCONSIN, A CORPORATION OF WISCONSIN.

PLACER-DREDGE BUCKET.

Application filed December 2, 1921. Serial No. 519,359.

To all whom it may concern:

Be it known that we, WALTER FERRIS and MATTHEW F. KEESE, being citizens of the United States, and residents, respectively, of Milwaukee, and of South Milwaukee, in the county of Milwaukee and State of Wisconsin, and whose post-office address is care of Bucyrus Company, South Milwaukee, Wisconsin, have invented a certain new and useful Improvement in Placer-Dredge Buckets, of which the following is a specification.

Our invention relates to placer dredging machinery, and particularly to dredge chains formed of connected buckets that form a continuous belt, the use of which is familiar to those acquainted with the dredging art.

Our invention has for one object to provide a bucket bottom with outwardly curving sides to which damp material will not adhere, to provide a bucket having a bottom substantially rounded and free from the sharp angles and pockets which are characteristic of the buckets now in use. In the past it has been the practice to use a bucket which, in a sense, forms a link in a chain, and the bottom of which lies within two link side members and is confined by them, having straight sides between which damp, sticky material tends to adhere. A further object is to provide a light casting and to avoid large, thick masses of metal which would interfere with heat treatment of the casting. A further object is to provide a cast bucket so perforated and provided with cores and apertures that the cooling water used during heat treatment will have access throughout the mass and good circulation during and after the heat treatment. A further object is to provide a bucket bushing which shall be particularly stable and safe from shifting in its seat, and which shall be adapted to prevent any escape of or wedging of the bushing between the bucket pin and the inner corners of the bushing engaging shoulders.

We illustrate our invention more or less diagrammatically in the following drawings, wherein:

Fig. 1 is a side view of a bucket chain; 50

Fig. 2 is a section on the lines 2—2 of Fig. 7 of a bucket link;

Fig. 3 is a section on the lines 3—3 of Fig. 2;

Fig. 4 is a section on the lines 4—4 of Fig. 2;

Fig. 5 is a section on the lines 5—5 of Fig. 2;

Fig. 6 is a section on the lines 6—6 of Fig. 2; 60

Fig. 7 is a top view of the bucket link;

Fig. 8 is a plan view of the bucket.

Like parts are indicated by like numbers throughout the drawings.

A is a cast placer mining bucket to which 65 is removably secured a cutting lip or element A¹⁰, the details of which form no part of the present invention. The bucket is cast integral with a link element which has at one end the single eye A' located at the center of the chain axis, and at the opposite end the opposed pair of eyes A² A² spaced at either side from the chain axis or longitudinal center line of the link, the space between being equal to the width of the eye A'. Extending forwardly from the eye A', its lower surface tangential to both eyes, is the tread plate A³ which supports the depending bottom A⁴ of the bucket A by means of the webs A⁵ A⁶ A⁷. The space between the webs 70 forms the passages A⁸ A⁹, which are open forwardly and project inwardly about the bottom A⁴ of the bucket. Preferably, they are each connected with the interior of the rear eye A' by passages A¹¹ A¹². There 75 may, if desired, be an opening in each of the passages A⁸ A⁹ to the bottom of the tread surface, as at A¹³ A¹⁴. The outer tread members A¹⁵ A¹⁶ projecting forwardly 80 from A³ are parallel.

The bottom A⁴ of the bucket, which is spaced away from the tread plate A³ and supported by the webs A⁵ A⁶ A⁷, depends slightly within the side link elements A⁵ A⁷, the upper line of which is indicated by the dotted line in Fig. 2. The bottom of the bucket, however, is sufficiently lifted to prevent any constriction between these side link 85 90 95

elements and to permit its bottom to be rounded or inclined without interference therewith, to show the contours indicated in Figs. 3-6. The link elements incline outwardly from the single eye to join the eyes A², and the parallel tread members A¹⁵, A¹⁶ at the end adjacent the eye A', link and tread are bound together by the webs B² B³. The rear eye A' is apertured as at C to form an aperture bounded by two concentric arcs of different radius, adapted to receive about substantially more than one-half of its circumference the inserted bushing C', the ends of which contact the opposed surfaces C² C³ in the body of the eye which form abutting surfaces of greater width than if placed diametrically opposed, since the outer sides of the bushing ends are parallel, forming lines tangential to the outer circumference of the bushing. The bottom A⁴ of the bucket is pierced by apertures D in each of which, during use of the bucket, a hardwood plug is driven after the bucket has been heat-treated.

It will be understood that while an operative device is herein shown and described, many changes might be made in the number, size and relation of parts without departing from the spirit of our invention.

The use and operation of our invention are as follows:

We have illustrated a bucket which forms a link having at one end a single centrally located eye and at the other end two eyes at the sides of the link. The chain used is composed of a plurality of these bucket links articulated, the side eyes being pinned through into the center eye by the usual form of bucket pins.

It has been past practice to employ a bucket link in which the bottom of the bowl penetrated far between the side elements of the link and formed part of the bearing surface or tread portion of the link. This had several disadvantages. In the first place, a large thickened mass of metal could only be avoided by dropping the bottom of the bowl between the links. The location of the bottom of the bucket near the lower extremity of the side elements made a perpendicular-sided bucket bottom necessary, in which the opposed sides were parallel and perpendicular to the bottom of the bucket. The upper portion of the bucket walls then flared out from the constricted bottom portion. The result was that the damp, sticky material lifted by the bucket tended to adhere to the constricted perpendicular lower walls and the bucket was therefore wasteful to use and required frequent cleaning and stoppage of the machine.

In the form shown, applicants have lifted the bucket above the bottom of the link, thus making it possible to curve the bottom walls

to make them a continuation of the outwardly flared upper walls, thus avoiding the tendency of material to gather and stick to the bottom. The result is a bucket having a substantially hemispherical bottom or end, entirely free from the angles, pockets and depressions which are so characteristic of the buckets now in use. This arrangement, furthermore, make possible the breaking up of a large bottom mass of the metal casting by a plurality of apertures or galleries through which a free circulation of water can pass during the heat treatment of the casting. The intermediate webs serve to strengthen the whole assembly and to support the bottom of the bucket.

The new arrangement provides immediately in front of the single eyelet, what is in effect a box girder, the two lateral vertical sides of which are made up of the link members, the lower horizontal side being made up of the laterally extended bearing web projecting forward and tangentially from the lower side of the eye, the upper side of the box girder being made up of the curved bottom of the bucket itself and contacting or terminating in a tangent to the upper side of the single eye. This box girder effect enables the most economical distribution of the metal and does away with the necessity of having a large mass concentrated at one point where heat treatment would be difficult and when initial shrinkage strains might be concentrated and cause structural or other weaknesses, while at the same time obtaining a well designed bucket interior.

In the earlier buckets the bushing C' formed one-half of an annulus, and in practice the bearing surfaces at its ends frequently became sufficiently worn and battered to permit the bushing to revolve in its seat and to wedge in between the pin and the inner wall of the bearing aperture. The present form makes this impossible, since the bushing is carried beyond the diametrically opposed points of the earlier bushing and its ends are opposed by more deeply recessed abutting surfaces. Experience has shown that the present form is substantially free from the objections above outlined and the bushing, when once seated, rests firmly in place and does not tend to escape.

We claim:

1. A link for excavator chains comprising a relatively long centrally located eye, link members forwardly and outwardly inclined from the opposite ends of said eye and terminating in a pair of opposed side eyes, a tread plate separate from and spaced below the bottom of the bucket, projecting forwardly from and tangent to the single eye and joining the lower edges of the link members.

2. A link for excavator chains comprising a relatively long centrally located eye, link members forwardly and outwardly inclined from the opposite ends of said eye and terminating in a pair of opposed side eyes, a tread plate projecting forwardly from and tangent to the single eye and joining the lower edges of the link members, reinforcing webs on the outer sides of the link members terminating in a plane substantially in line with the outer sides of the side eyes. 65
3. A chain for bucket excavators comprising a plurality of separate links having each a central pivot sleeve and link members forwardly and outwardly inclined from the opposite ends of said sleeve, said link members terminating in eyes, the distance between the opposed eyes being substantially equal to the length of the sleeve, and spacing webs on the outside of the link members extending rearwardly from the eyes to a point adjacent the sleeve, to provide a chain having parallel sides. 75
4. An integrally cast bucket for excavators comprising a link member having a tread plate on the bottom of the link extending from side to side thereof, and a bucket mounted on the top of the link and having its bottom above and over-lying the tread plate, and separated therefrom by an open intervening space. 80
5. A bucket member for chain excavators comprising a link having a central bearing sleeve and a bucket mounted on the link, the bottom of the bucket terminating above the bottom of the link and a tread plate spaced from the bottom of the bucket and tangent to and integral with the sleeve. 85
6. A bucket for excavator chains comprising a link member and a bucket member integral therewith, a tread plate integral with the link member separated from the body of the bucket and a core passage located within the link between it and the bucket member to permit water circulation for heat treatment. 90
7. An integrally cast bucket for chain excavators comprising a link member having a pair of substantially vertical, substantially parallel side elements, a bucket integral with and mounted on the top of said link member and supported by said side elements, the bottom of the bucket being substantially as high above the bottom of the link as are the tops of the link side elements, and a tread plate extending from side to side of the bottom of said link, underlying said bucket bottom and separated therefrom by an open intervening space. 95
8. A bucket element for chain excavators comprising a link member having side link elements, a bucket mounted on the link member, its bottom substantially even with the tops of said link members, and a tread plate parallel with the bottoms of said link members, and out of contact with, and spaced from the bottom of the bucket. 100
9. An integrally cast bucket for excavators comprising a link member, a bucket cast integrally therewith, a tread plate upon the bottom of said link member extending from side to side thereof, underlying and vertically separated from the rear of said bucket bottom by an open intervening space. 105
10. A bucket for excavator chains comprising a link member and a bucket integral therewith, a tread plate lying beneath and spaced from said bucket bottom, supporting webs between said bucket bottom and tread plate, and apertures therebetween opening into the space between the sides of the link. 110
11. A bucket for excavator chains comprising a link member, a single perforated lug at one end, and a double perforated lug at the other, side webs connecting said lugs, and tread plate connecting said side webs and said single lug, a bucket portion integral and joining said side webs, and core openings extending between the lowest portion of said tread plate and said bucket portion. 115
12. A bucket for excavator chains comprising a link member, a single perforated lug at one end, and a double perforated lug at the other, said webs connecting said lugs, and tread plate connecting said side webs and said single lug, a bucket portion integral and joining said side webs, and core openings extending between said tread plate and said bucket portion, and communicating with the perforations of the single lug. 120
13. A bucket for excavator chains having at one end a single perforated lug, a tread plate projecting forwardly from the bottom of said lug, a bucket projecting substantially forwardly and downwardly from the top of said lug, link side members joining said bucket and said tread plate, said bucket and tread plate being separated by open spaces intermediate said link side members. 125
14. A bucket member for chain excavators comprising a link having a central bearing sleeve and a bucket mounted on the link, the bottom of the bucket terminating above the bottom of the link, a tread plate projecting forwardly from and tangent to and integral with the sleeve, and a separating web joining said tread plate and said bucket bottom, the wall of the sleeve being apertured to communicate with the space between the bucket bottom and the tread plate. 130
15. An integrally cast bucket for excavators comprising a link member having a tread plate on the bottom of the link and extending from side to side thereof, and a bucket extending from side to side of said link member, the bottom of said bucket over-lying said tread plate and vertically separated therefrom by an intervening open

space, the forward edge of said tread plate underlying the lowest portion of the bucket bottom.

16. An integrally cast bucket for excavators comprising a link member having a tread plate on the bottom of the link extending from side to side thereof, and a bucket mounted on the top of the link and having its bottom above and overlying the tread plate and separated therefrom by an

open intervening space, said space being open in the direction of the front of the link.

Signed at South Milwaukee, Wisconsin, this 29th day of November, 1921. 15
